(57) **CLAIM**

The ornamental design for a display screen or portion thereof with animated graphical user interface as shown and described.

DESCRIPTION

FIG. 1 is a front view of a first image of a display screen or portion thereof with animated graphical user interface showing my new design;

FIG. 2 is a front view of a second image thereof; and,
FIG. 3 is a front view of a third image thereof.

The broken lines around the figure show a display screen or portion thereof and form no part of the claimed design.
The appearance of the transitional image sequentially transitions between the images shown in FIG. 1-3. The process or period in which one image transitions to another image forms no part of the claimed design.
